UNITED STATES PATENT OFFICE.

JOSEPH H. ARENDS, OF CHICAGO, ILLINOIS.

AUTOMATIC STOP AND REPLAYING DEVICE.

Application filed August 13, 1921. Serial No. 491,964.

To all whom it may concern:

Be it known that I, JOSEPH H. ARENDS, a citizen of the United States, residing at Chicago, in the county of Cook and State 5 of Illinois, have invented certain new and useful Improvements in an Automatic Stop and Replaying Device, of which the following is a specification.

My invention relates to a combined automatic stop and replaying device for phonographs and has for its particular object the combination of a device which can be used as an automatic stop when the playing of a record has been completed, or which will 15 automatically transfer the sound box and tone arm back to the starting point on the record and play the record over again as many times as may be desired.

Another and further object of my invention 20 is the provision of a replaying device which can be set so as to play a record an indeterminate number of times or which can be so set that the record will be played a predetermined number of times and when 25 the operation is completed a brake will be automatically applied to the turn-table of the phonograph and its operation stopped.

Another and further object of my invention 30 is the provision of a replaying apparatus which provides a minimum load upon the motor of the phonograph and which requires only a small force to operate it and also in which there is no side thrust upon the shaft leading from the turn-table to the 35 motor, as is the case with the phonograph replaying apparatus which have been heretofore designed.

Another and further object of the invention 40 is the provision of a replaying apparatus which is simple in operation and which can be easily adjusted to play a record of any size, or which can be dispensed with entirely and the phonograph operated in the usual manner.

These and other objects of my invention 45 will be more fully and better understood by reference to the accompanying sheets of drawings, in which—

Figure 1 is a plan view of my improved 50 invention;

Figure 2 is a vertical sectional view of the bracket to which the repeater bar is secured;

Figure 3 is a vertical end view of the 55 bracket shown in Figure 2;

Figure 4 is a detailed view in elevation

of the tone arm and bracket along the line 4—4 of Figure 1; and

Figure 5 is a side elevational view of the base of the tone arm and the stop for actuating the device.

Referring now specifically to the drawings, and in which like reference characters refer to like parts throughout, a phonograph cabinet 10 is shown having a motor board 65 11 secured thereto in the usual manner. A turn-table 12 is provided having a downwardly turned flange 13 thereon against which the brake is applied as hereinafter described. A ring member 14 is provided 70 which is secured to the motor board 11 by means of screws 15 which pass through the base or flange portion of the member 14 and which rests securely against the motor board 11. A tone arm 17 is mounted within the 75 member 14 in the usual manner, and is curved upward and towards the forward portion of the phonograph and over the turn-table in the usual manner and has a sound box secured thereto at its outer end 80 in the usual manner common to phonographs. The turn-table 12 is mounted upon a motor shaft 18 which leads to the motor and which may be either the usual type of 85 spring motor or electric motor with which phonographs are frequently provided. Secured to the shaft 18 is a gear wheel 19 which is positioned below the turn-table upon which the record rests while being played. A second gear wheel 20 is provided 90 which is secured to the motor board by means of a screw 21, the gear wheel 20 having a smaller gear wheel 22 secured thereto or integrally therewith, as may be desired, the gear wheel 20 being in mesh with the 95 wheel 19 and at all times is rotated whenever the phonograph is being played. A draw bar 23 is provided which is pivotally secured to a power bar 24 also pivotally mounted to the motor board 11 by means of 100 a screw 25, a pin 26 serving to connect the bars 23 and 24 together. Secured to the power bar 24 is a gear wheel 27, the wheel 27 having an offset portion 28 and being normally out of engagement with the small gear wheel 22 except when the tone arm is being transferred to the outer part of the record, as hereinafter described. The power bar 24 is connected to the wheel 27 by means 105 of a pin 29 at one side of the center of said wheel so that as the wheel 27 is rotated the power bar 24 will be given a reciprocatory

110

movement, as hereinafter described. A member 30 is secured to the motor board by means of screws 31 and having a vertically looped portion 32 which extends 5 above the motor board 11 and has the end of the bar 23 inserted between the portions of the looped member 30 so that the said member forms a guide-way for the end of the bar 23 as it is moved backward and 10 forward. Mounted within the loop 32 of the member 30 is a crank member 33 having a downwardly extending portion 34 which is inserted into an opening 35 in the end of the draw bar 23. Secured to the 15 member 33 is a repeater bar 36 by means of a pin 37 or in any other approved manner and which is adapted to be tilted upward by the draw bar 23 during the operation of the device. Secured to the end of the bar 20 36 is a small pin 38 which projects downwardly and has a spring 39 secured thereto and which is secured to a pin 40 in the wall of the loop 32, the purpose of this 25 spring being to hold the repeater bar to one side of the turn-table and out of the way of removal of a record if the replaying device is not being used.

It will be understood that the repeater bar 36 extends across the face of the turn-table 30 12 and underneath the sound box and is tilted upward by the action of the lever 23 as hereinafter described, so that the sound box slides along the repeater bar 36 toward the outer edge of the record until it is 35 caught by a stop 41 adjustably secured to the repeater bar by means of a screw 42 so that the outward movement of the sound box is stopped at the proper position to insure the sound box needle being positioned into 40 the outer sound groove of the record. A clip 43 is secured to the base of the tone arm 16 by means of screws 44 and has an outwardly projecting lug 45 to which a clip 46 is secured by means of a pin 47. Mounted within 45 the clip 46 is a crank member 48 having a downwardly projecting pin 49 secured thereto and a button 50 on the outer end thereof so that the device may be easily set, as desired. The member 48 is held in the 50 frictional engagement of its sides with the clip 46 so that the position of the pin 49 may be changed to any desired position to cause the brake to be applied to the turn-table or operate the repeating apparatus, as herein- 55 after described.

Secured to the motor board 11 by means of a screw 51 is a V-shaped lever 52 having a projection 53 on its ends adjacent the draw bar 23 and which engages against the 60 shoulder 54 formed on the draw bar 23 and which serves to normally hold the gear wheel 27 out of engagement with the gear wheel 22. A clip 55 is secured to the motor board having a set screw 56 therein and against 65 which the lever 52 abuts when operated by

the pin 49 in the member 48 so that the movement of the lever 52 is limited by the screw 56 in the clip 55. Secured to the end of the draw bar 23 by means of a pin 57 is a lever 58 which is secured to the motor board 11 by means of a screw 59, the screw 59 passing through a fan shaped member 60 which turns upon the screw 59 and which forms a regulator for the operation of the device. An arm 61 integral with the member 60 is provided in the end of which a button 62 is inserted having a pointer 63 positioned in the end thereof for the purpose of indicating the proper position of the arm 61. The member 60 in its marginal edge has a deep recess 64 therein and has in its periphery on each side of the recess 64 notches 65 and 66. A brake member 67 is provided which is secured to the motor board by means of a screw 68 and has an L-shaped end 69 with a roller 70 mounted in the end thereof which is adapted to seat in the recess 64 or in any of the notches 66 during the operation of the device. A yielding brake element 71 is secured to the brake member 67 and which is adapted to contact with the flange 13 on the turn-table 12 when the brake is in position to stop the operation of the machine. Secured to the end of the member 67 is a spring 72 which is fastened to the motor board 11 by means of a screw 73, the member 67 also having a rod 74 secured thereto, the opposite end of which is adapted when the brake is set in the machine to fit into a notch 75 on the side of the draw bar 23, thus serving to lock the draw bar 23 until the rod 74 is pulled out of the notch 75 by the action of the member 60 when it is turned and set in any desired position. A clip 76 is secured to the rod 74 and a spring 77 secured thereto which in turn is fastened to the arm 58 and serves to pull the arm 58 against the pin 86, thus pulling the catch 83 out of the notches 65. The hole in the bar 58 through which the pin 57 passes is sufficiently large to allow a slight movement of the arm 58. A spring 78 is secured to the end of the arm 52 in a notch 79, the opposite end of the spring being secured to a notch 80 in the draw bar 23 and this spring also assists in pulling the driving wheel 27 into engagement with the small pinion 22. An indicator plate 81 is provided which is secured to the motor board by means of screws 82, 82, and over which the handle 61 of the indicator 85 extends. The plate 81 has markings thereon to indicate the various positions of the arm 61 in the set of the device such as "Repeat only" at one end thereof, "Automatic stop" 90 at the other end, and in between these points from "1" to "5", indicating the number of times a record can be played until the brake will be applied to the machine. In the position shown in the drawings the brake is 95

100

105

110

115

120

125

130

135

applied to the turn-table 12 and the turn-table therefore held against rotation. A catch 83 is secured to the member 58 by means of a pin 84 and has a spring 85 mounted thereon which is adapted to push the member 83 downward into engagement with the notches 65 on the marginal edge of the member 60. A pin 86 is inserted in the motor board and contacts with the 10 upper end of the member 83 so that in the position of the device shown in the drawings the device 83 will not engage in the notches 65 on the edge of the device 60, but is held above the edges of the notches 65 so that the 15 device 60 can be turned freely about the member 59. Immediately upon the arm 58 being pushed back the member 83 will be pushed down into contact with the member 60 and engage the notches 65 until the 20 arm 58 is pulled into the position shown in the drawings when the device 83 will abut against the pin 86, thus lifting the end 83 out of the notches.

In the operation of the device the tone 25 arm having the sound box mounted on the end thereof is grasped by the operator and moved until the needle of the sound box is over the outer groove of the record and the stop 41 on the repeater bar 36 set in the 30 proper position so that the sound box will be placed in contact with the record at the outer sound groove of the record. The tone arm is thereupon pushed to the innermost sound groove of the record and the stop 48 35 set in proper position for the pin 49 to engage the end of the lever 52 so that when the sound box plays to the last sound groove the pin 49 will engage against the end of the lever 52 and pull the end 53 of the lever 40 52 over the shoulder 54 in the draw bar 23 and allowing the wheel 27 to come into mesh with the small wheel 22.

In the operation of the device, as shown 45 in the drawings, the brake member 67 is engaged in the recess 64 of the member 60 and the device is in locked position. If it is desired to set the machine so that it will constantly repeat, the player grasps the button 62 on the end of the lever 61 and turns the device around to the point "Repeat 50 only" on the indicator 81. The turning of the member 60 to this position releases the brake 71 against the turn-table 12 and allows the roller 70 to become seated in the 55 lowermost notch 66 in the member 60 and also holds the rod 74 out of the recess 75 in the draw bar 23, thereupon the phonograph starts to play and the sound box following the grooves on the record until the 60 innermost groove is reached, whereupon the tone arm has been turned until the pin 49 contacts with the end of the lever 52 which raises the opposite end of the lever 52 out of the notch 64 and allows the spring 78 65 to pull the driving wheel 27 into engage-

ment with the wheel 22 which starts to rotate and cause a reciprocatory movement to the draw bar 23 through the action of the member 24 which is secured to the wheel 27. As the member 23 reciprocates the 70 crank 33 is turned and lifts the repeater bar 36, the outer end of the repeater bar being tilted upward so that the sound box slides along the repeater bar until it contacts with the stop 42 whereupon the repeater bar is held down in the position shown in Figure 2, whereupon the sound box contacts with the record, the needle in the sound box is seated in the outer groove and the device commences playing the record over again. The member 83 on the bar 58, during the operation just described, is positioned on the marginal edge of the member 60 immediately adjacent the recess 64 and does not engage in any of the notches 65 so that the device set in this position will continue to play as long as power is supplied through the motor. If it is desired 80

to play a record say five times, the bar 61 is pulled around to the figure 5 on the repeater bar, whereupon the roller 70 will be engaged in the second notch 66 on the marginal edge of the member 60, and when the operation described above takes place at the time the record is played the member 83, owing to the movement of the lever 58, will engage in one of the notches 65 and will automatically turn the handle 61 back to 4 on the indicator and as the device continues 90 playing each time the record is played the device 60 is rotated one point until the position of "Auto-stop" is reached on the indicator and after a record has been played with the arm in this position the brake is applied to the turn-table, thus effectively 100 stopping the operation of the turn-table.

As the member 60 is turned so that the roller 70 is in the lowermost notch 66, the member 83 contacts with the smooth outer periphery of the member 60 adjacent the notch 64, so 110 that this member 83 does not engage in one of the notches 65 when the device operates to return the tone arm to the outer side of the record, so that this operation is repeated indefinitely if the phonograph is operated by an electric motor or until the spring motor runs down or until some change is made in the mechanism so the member 83 will engage in the notches 65. It will thus be understood that, as the device 115 is shown, a record can be repeated an indefinite number of times or it can be repeated any number of times up to and including 5, and the device may also be used simply as a brake by setting the arm 61 at the position of "Auto-stop" on the indicator, whereupon the record will be played once and the brake applied after the record has been played. It will also be understood 120 that the arm 36 can be turned around along 125

side of the turn-table as a pivotal movement is permitted upon the pin 37, so that if it is desired to operate the machine by hand and use the device as a hand brake the machine 5 can be played and controlled by hand operation in the usual manner.

While I have described more or less precisely the details of construction, I do not wish to be understood as limiting myself 10 thereto, as I contemplate changes in form and the proportion of parts and the substitution of equivalents as circumstances may suggest or render expedient without departing from the spirit or scope of my invention.

I claim:

1. In a record replaying device for phonographs comprising in combination with the motor board of a phonograph, a slidably 20 mounted draw bar, a repeater bar, operative connections between the said draw bar and the said repeater bar, a pivotally mounted power bar secured to said draw bar, a mutilated gear eccentrically mounted upon said 25 power bar, a train of gears connected to the motor shaft, tripping means mounted on the tone arm and a tripping lever adapted to release the slidably mounted draw bar whereby the said mutilated gears are brought to 30 engagement with each other and the draw bar reciprocated, thereby moving the free end of the tone arm towards the outer side of the turn-table.

2. In a record replaying device for phonographs comprising in combination with the motor board of a phonograph, a slidably mounted draw bar, a loop secured to said motor board, a crank pivotally mounted in 35 said loop and connected to said draw bar, a repeater bar connected to said crank member, a power bar, a mutilated gear, a train of gears connected to the motor shaft, tripping means carried by the tone arm and a pivotally mounted lever, one end of said 40 lever being engaged by the tripping lever on the tone arm when the said tone arm reaches a predetermined position near the inner portion of the record, the opposite end of said lever holding said draw bar whereby the said gears are normally held out of 45 engagement with each other, but adapted to be brought into engagement with each other when the said draw bar is released.

3. In a record replaying device for phonographs comprising, in combination with the motor board of a phonograph, a slidably mounted draw bar, a pivotally mounted crank member connected to said draw bar at one of its ends and having its other end 50 extending partially across the turn-table of the phonograph under the sound box, a pivotally mounted power bar secured to the motor board at one of its ends and to the draw bar at its other end, a mutilated gear 55 eccentrically mounted upon said power bar,

gearing connected to the motor shaft of the phonograph in normal out of engagement with said mutilated gear, spring means connected to said draw bar, a pivotally mounted detaining lever in engagement with said draw bar at one of its ends and a stop carried by the tone arm adapted to engage said pivotally mounted lever, thereby releasing the said draw bar and causing the said gears to come into engagement with each other, thereby reciprocating the said draw bar and moving the free end of the tone arm from the inner toward the outer position of the turn-table.

4. In a record playing device for phonographs comprising, in combination, a motor board of a phonograph, a slidably mounted draw bar, a pivotally mounted crank member connected to said draw bar at one of its ends, the other portion of said crank member extending partially across the turn-table of the phonograph at right angles to the direction normally occupied by the tone arm, a pivotally mounted bar connected to said draw bar at one end and to the motor board at its other end, a gear carried by said power bar eccentrically mounted thereon, a train of gears connected to the motor shaft, a lever mounted on said motor board in normal engagement with said draw bar, a trip carried by the said tone arm adapted to engage said lever at one of its ends, the said gears being normally held out of engagement with each other, but adapted to be placed into engagement by the release of the draw bar whereby the tone arm is moved from the inner portion towards the outer edge of the turn-table of the phonograph.

5. A record replaying device for phonographs, comprising in combination with the motor board of a phonograph, a slidably mounted draw bar, a pivotally mounted crank member connected to said draw bar at one of its ends, the other end of said crank member extending partially across the turn-table and underneath the sound box of the phonograph, a pivotally mounted power bar connected to said draw bar at one of its ends and secured to the motor board at its other end, a mutilated gear eccentrically mounted upon said power bar, gears connected to the motor shaft of the phonograph, a bell crank lever in engagement with said draw bar at one of its ends, a spring secured to said bell crank lever and to said draw bar, a tripping member carried by the tone arm adapted to engage said bell crank lever whereby when the draw bar is disengaged from said bell crank lever, the mutilated gear is forced into mesh with one of said gears connected to the motor shaft, and a locking member adapted to positively lock the mechanism after a record has been played a predetermined number of times.

6. A record replaying device for phonographs, comprising in combination with the motor board of a phonograph, a slidably mounted draw bar, a pivotally mounted crank member connected to said draw bar at one of its ends, the other end of said crank member extending partially across the turn-table and underneath the sound box of the phonograph, a pivotally mounted power bar connected to said draw bar at one of its ends and secured to the motor board at its other end, a mutilated gear eccentrically mounted upon said power bar, gears connected to the motor shaft of the phonograph, a bell crank lever in engagement with said draw bar at one of its ends, a spring secured to said bell crank lever and to said draw bar, a tripping

member carried by the tone arm adapted to engage said bell crank lever whereby when the draw bar is disengaged from said bell crank lever, the mutilated gear is forced into mesh with one of said gears connected to the motor shaft, a rotatably mounted segmental control member, a brake operated by the said segmental control member after a record has been played a predetermined number of times, and a locking rod operated by the said brake and adapted to lock the said mechanism against movement when the brake is in engagement with the turn-table.

Signed at Chicago, Illinois, this 2nd day of August, 1921.

JOSEPH H. AREND'S.
